US0D1043566S

(12) **United States Design Patent** (10) **Patent No.:** **US D1,043,566 S**
(45) **Date of Patent:** **** Sep. 24, 2024**

(54) **WIRELESS CHARGER**

(71) Applicant: **Samsung Electronics Co., Ltd.**, Suwon-si (KR)

(72) Inventors: **Syeon Lee**, Suwon-si (KR); **Jaehyung Hong**, Suwon-si (KR)

(73) Assignee: **SAMSUNG ELECTRONICS CO., LTD.**, Gyeonggi-Do (KR)

(**) Term: **15 Years**

(21) Appl. No.: **29/860,468**

(22) Filed: **Nov. 18, 2022**

(30) **Foreign Application Priority Data**

Sep. 5, 2022 (KR) 30-2022-0036107

(51) **LOC (14) Cl.** **13-02**

(52) **U.S. Cl.**

USPC **D13/108**

(58) **Field of Classification Search**

USPC D13/103, 107, 108, 118, 119, 183, 184, D13/199; D14/432, 434, 439, 447, 251, D14/252

CPC H02J 7/0044; H02J 7/0045; H04B 1/3877

(57) **CLAIM**

The ornamental design for a wireless charger, as shown and described.

DESCRIPTION

FIG. 1 is a top perspective view of a wireless charger, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of a wireless charger that form no part of the claimed design.

1 Claim, 3 Drawing Sheets
